(57) **CLAIM**

The ornamental design for a cardiac ultrasound concave phased array transducer, as shown and described.

DESCRIPTION

FIG. 1 is a front perspective view of a cardiac ultrasound concave phased array transducer;

FIG. 2 is a top view thereof; and,

FIG. 3 is a left view thereof.

The broken lines depict portions of the cardiac ultrasound concave phased array transducer that form no part of the claim.

1 Claim, 3 Drawing Sheets

FIG. 1

FIG. 2

FIG. 3
